UNITED STATES PATENT OFFICE.

JOHN CUTHBERT, OF CHICAGO, ILLINOIS.

FORMING MACHINERY.

No. 905,852.

Specification of Letters Patent.

Patented Dec. 8, 1908.

Application filed October 1, 1906. Serial No. 336,835.

To all whom it may concern:

Be it known that I, JOHN CUTHBERT, citizen of the United States, residing at Chicago, in the county of Cook and State of Illinois, have invented a certain new and useful Improvement in Forming Machinery, of which the following is a full, clear, concise, and exact description, reference being had to the accompanying drawings, forming a part of 10 this specification.

My invention relates to stamping and forming machinery and has for its object the provision of a machine of this class which will be of greater efficiency and of more simple construction than the machines of this 15 kind of the prior art.

It is one of the primary objects of my invention to provide a machine which will do in one operation what has heretofore been done in three or four and which will be free from 20 the complex and intricate mechanism which has heretofore been employed in attempts to construct machines which would secure these desirable results.

Broadly speaking, the machine of my invention is a press which is provided with stamping devices and forming dies which operate with each stroke of the press slide to stamp and form the blanks which are fed 30 into the machine to produce the desirable article.

It is one of the features of my machine that delicate adjustment is not required, and that all that need be done manually is to feed the blank, for instance, a metal ribbon, 35 into the machine. This feature eliminates the necessity of an experienced operator and thereby lowers the cost of production of the article manufactured.

Another of the important features of my 40 device is that the various operating parts are in plain view and are of easy access so that they may be easily reached and manipulated in case of necessity of repair. I provide a 45 construction, the operation of which is simple and positive and which does not easily become disarranged or disordered. The construction is such that the machine may be operated by small power which further decreases the expense of production. The 50 construction is such that the blank being fed into the machine is first stamped and is then advanced to the forming mechanism where it is formed into the finished article. The stamping 55 mechanism and the forming mechanism operate simultaneously but not upon the

same portion of the blank. Upon the same stroke during which dies are forming into the finished article the furthermost advanced portion of the blank, the stamping mechanism operates to punch another portion of the blank. By this feature, the machine is able to complete a finished article upon each stroke of the punch slide.

The operation and the construction of the machine will be more readily understood by reference to the accompanying drawings in which

Figure 1 is a front elevation of the machine; Fig. 2 is a side elevation thereof; Fig. 3 is a plan view thereof, that portion of the machine above the line 3 of Fig. 2 being removed; Fig. 4 is an elevation view of the die and punching mechanisms on a larger scale; Fig. 5 is a detached sectional view on the line 5—5 of Fig. 3; Fig. 6 is a detached sectional view on the line 6—6 of Fig. 3; Fig. 7 is a detached sectional view on the line 7 of Fig. 3; Fig. 8 is a view of one form of blank which may be fed into the machine, showing the blank after it has been stamped; Fig. 9 is a view of the finished article formed from the blank shown in Fig. 8 by means of the dies shown in Figs. 1, 4, 5 and 6; Fig. 10 is a side view thereof; Fig. 11 is a view illustrating another form of die which may be employed; Fig. 12 is a sectional view on the line 12—12 of Fig. 11; Fig. 13 is a view of another form of blank which may be fed into the machine, showing in dotted lines the shape of the blank after having been stamped; Fig. 14 is a view of the finished article formed from the blank 13 by the dies shown in Figs. 11 and 12.

The machine frame 1 is supported by the 95 legs 2 and 3 which are bolted thereto and are held together by means of the tie rods 4. The upper part of the frame consists of the uprights 5 and 6 which terminate at their upper ends in the bearings 7 and 8. The 100 various mechanisms, as will be hereinafter described, are mounted on the bed 9 of the frame, and the bolster plate 10 is mounted thereon and secured thereto by any suitable means.

Mounted in the bearings 7 and 8 is the main shaft 11 which is provided at one end with the loose pulley 12 which is adapted to be brought into operative engagement with the shaft by means of the clutch collar 13 110 which is keyed to the shaft but is slidable thereon. The main shaft 11 is also provided

with the crank 14, the pitman 15 being mounted therein as shown in the drawings. The lower end of the pitman 15 is pivoted to the slide 16 which is mounted in the gibs 17 and 18, these gibs being secured to the framework by means of the bolts 19, 19. To the slide 16 is secured by means of the bolts 20, 20 the supporting member 21 which supports the forming and stamping mechanism. The supporting block 22 is secured to the member 21, and the punches 23 are mounted in this supporting block. To the supporting member 21 is also secured by means of the bolts 24, 24 the cam plate 25, which is adapted to reciprocate therewith and to ride in the slot 26 cut in the bolster plate 10. To insure against the disarrangement of the parts operating in the slot 26, the cap plate 27 is secured to the front of the bolster plate, as shown in the drawings. Suspended from the pivots 28 and 29 in the supporting member 21 are the die or forming members 30 and 31 respectively. These dies, as will be hereinafter described, are adapted to operate with the punch slide and are adapted to operate with the cam plate 25 in the slot 26. The forming members 30 and 31 are adapted for association with the die members 32 and 33, the die member 32 being part of a block 34 which is mounted in a slot 35 in the apron 36 of the frame, and is made adjustable in said slot by means of the screw mechanism 37. Lock bolts 38, 38 are provided to hold the die in any desired position. The stock which is being fed into the machine is shown at 8 and is advanced until it reaches the stop 39. The machine is then set in motion, and the plunger, which normally rests in its upward position, descends. The former 31 is provided with an extension 40 which has the knife edge 41, and as the slide descends, this knife edge in conjunction with the shoulder 42 of the bolster plate 10 cuts the stock at this point. Further downward motion of the slide causes the formers 30 and 31 to draw the stock about the die 33. When the slide has reached its lowest position, the formers are forced toward the inside dies 32 and 33, the mechanism for securing this result being as follows: Pivoted at 42' and 43 to the apron 36 are the dogs 44 and 45 respectively, these dogs being in the form of bell crank levers, as shown in the drawings. The lower arms of the dogs are provided with the lateral extensions 46 and 47, the adjusting bolts 48 and 49 having threaded engagement with these extensions 46 and 47 respectively. Normally these dogs are held in the position shown in Fig. 4 by means of the springs 50 and 51 which are interposed between the frame and the upper arms of the dogs, as is clearly shown in the drawings. When the cam plate descends, the cam surface 52 thereof engages the upper end of the bolts 48 and 49. This causes the

lower arms of the dogs to be forced downwardly until the cam plate has assumed the position shown in the dotted lines in Fig. 4. The springs 50 and 51 are then distended, and the dogs assume the position shown in dotted lines in this figure. The dogs preferably have the extensions 46 and 47 leading forwardly at right angles to the main portion thereof, whereby the cam plate 25 may engage the extensions in order that it may properly operate them. The relative lateral disposition of these parts is shown in dotted lines in Fig. 2. The formers 30 and 31 are suspended in the same plane with the main portion of the dogs, so that when the slide descends and the cam plate forces the dogs about their respective pivots, the upper lever arms of the dogs may engage the outer surface of the formers, forcing them inwardly, whereby they are made to assume the position shown in dotted lines in Fig. 4.

In order that the finished article may drop from the dies when the outside formers have been removed therefrom by the upward stroke of the slide, mechanism is provided to draw the die 33 backward in a slot in the bolster plate 10 in which it rides, whereby the finished article may be stripped therefrom and dropped into a receptacle below the machine. Mechanism for securing this result is shown in the various figures and particularly in Figs. 3 and 5. Secured to the shaft 11 is the sprocket wheel 53. Mounted in bearings 54, 54 is the shaft 55 which is provided with the sprocket wheel 56, this sprocket wheel and the sprocket 53 being operatively connected by means of the sprocket chain 57. Secured to the shaft 55 is the cam 58, best shown in Fig. 5. The cam follower 59 adapted to be operated by this cam is mounted upon the bed 9 and is adapted to slide between the guides 60 and 61. This cam follower is connected with the inside die 33 by means of the rod 60'. Adjustably mounted upon the connecting rod 60' is the arm 61' between which and the cross piece 62 of the frame is connected the spring 63. This spring holds the follower 59 in close engagement with the cam surface of the cam 58. It is evident from the drawings that a complete revolution of the shaft 55 in the direction of the arrow 64 would cause a movement of the follower and the associate die 33 from the position shown in Fig. 5 to the position shown in dotted lines in this figure. The cam 58 is of such shape that over half a revolution is completed before the backward movement of the follower and the die 33 is commenced. This cam is so timed with regard to the connection of the shaft 55 with the main shaft 11 that this backward movement will be begun directly after the beginning of the upward stroke of the slide. As has been before stated, and as is evident from an examination of Fig. 4, the formers 30 and 31

are released immediately upon the commencement of the upward stroke of the slide. Thus, the die 33 is withdrawn directly after the release of the formers 30 and 31, this release being caused by the release of the dogs from contact with the cam plate 25. By the employment of this mechanism, the formers 30 and 31 are released from the finished article which has been formed about the die 33, and immediately thereafter the die 33 is drawn backwardly whereby the finished article is stripped therefrom and may drop into a receptacle below. In order that the stock may be held securely upon the die 33 while the forming is taking place, that is, during the downward stroke of the slide and the consequent operation of the dogs and formers 30 and 31, I provide the gripping mechanism shown in the various figures and particularly in Figs. 3 and 6. A shaft 65 is mounted in suitable bearings, and a sprocket wheel 66 is secured thereto, as clearly shown in Figs. 3 and 6. The shaft 55 is provided with a sprocket wheel 67, and this sprocket wheel is connected operatively with the sprocket wheel 66 by means of the sprocket chain 68. Also secured to the shaft 65 is the cam member 69 which has as its follower the arm 70 of the lever 71, this lever being pivoted at 72 in the bearing 72' in the cross-piece 62. A spring 73 is connected between the frame and the lever 71, as shown in Fig. 6, whereby the arm 70 may be held in close engagement with the cam surface of the member 69. A grip 74 is provided and is mounted in the dove-tail slot 75 in the cross-piece 62 and is adapted to operate therein. At its upper end the grip 74 is provided with the pivot 75', this pivot being in engagement with the elongated slot 76 in the arm 77 of the lever 71. From an examination of Fig. 6, it will be noted that a complete revolution of the shaft 65 will cause a movement of the lever 71 about this pivot, whereby it is made to assume the position shown in dotted lines in this figure. This will cause the downward movement of the grip 74, whereby it is brought into engagement with the stock upon the die 33. This will hold the stock firmly in place until the further rotation of the shaft 65 has caused its release by reason of the advance of the cam 69. The sprocket wheels 66 and 67 are preferably alike, so that a complete revolution of the shaft 55 will cause simultaneously a complete revolution of the shaft 65. The cam 69 is so timed that it will hold the lever 71 in the position shown in dotted lines in Fig. 6 during the time that the formers are drawing the stock about the inside dies. Thus, the grip 74 holds the stock firmly while the forming is taking place. Thus, while the formers 30 and 31 are drawing the stock about the inside dies, the stock is firmly held in place by the grip 65 and immediately upon the release of the

formers 30 and 31, the grip 74 releases the stock, and the die 33 is drawn inwardly whereby the finished article is allowed to drop into the receptacle below.

In order to further secure against any displacement of the stock while it is being punched or while the forming is taking place, I provide the mechanism shown particularly in Figs. 3 and 7. The shaft 65 is provided at its ends with the cam 78, the shape of which is clearly shown in Fig. 7. Pivoted to the support 79 at 80 is the lever 81, the arm 82 of which is adapted to engage the cam, and the arm 83 of which is adapted to engage the stock s, as shown in Figs. 3 and 7. Secured at its end to the arm 82 is the spring member 84 which is engaged by the bolt 85 passing through the arm 82 and which is adapted to form the engaging surface for the cam 78. It is evident that by the proper manipulation of the bolt 85, the proper disposition of the wearing surface of the spring member 84 may be obtained to secure the proper operation of the lever member 81, so that its arm 83 will securely engage the stock s. The cam 78 is of such shape that the stock s will be firmly engaged by the arm 83 during an entire revolution of the shaft 65 except for a short space of time, this short release of the stock being caused by the disposition of the part 86 of the cam surface. The cam 78 is so timed with regard to the other operative mechanism associated therewith that the stock will be released during that time that the knife edge 41 is above the horizontal plane of the stock and at the time when the stock can best be advanced to the stop 39. The operator of the machine can exert a constant forward push upon the stock to advance it toward the stop 39 but can feed it only when the dies and associated mechanisms are in position to receive it. The cams are so adjusted that the stock will be gripped, and immediately thereafter the slide will descend, whereby the knife 41 will cut the stock, as has heretofore been described. To prevent any lateral movement of the former 31 while the knife edge 41 is brought into engagement with the stock, a guide block 86' is provided upon the cross-piece 62 which engages the side of the projection 40. The other side of the former 31 is in engagement with the stop 74, as shown in Fig. 4, so that a positive direct downward movement of the knife will be afforded.

As has been stated before, the clutch collar is keyed to rotate on the shaft 11 but it is longitudinally slidable thereon. A bell crank lever 87 has a forked end which engages the clutch collar and is pivoted at 88 in the pivot block 89 secured to the machine frame. The other arm of the bell crank lever is connected through a cable or chain 90 with the treadle bar 91 which is pivoted to the machine frame at 92. Upon downward

pressure on the treadle the bell crank lever is rotated and the clutch collar slid to the right into clutching engagement with the pulley 12 and the machine is started. It is 5 desirable that the machine be automatically started when stock fed into the machine reaches the proper position to be operated upon. This, I accomplish electrically by solenoid mechanism comprising a winding 10 93 inclosed in a frame 94 suitably secured to the machine frame by means of bolts 95. A core 96 for the winding is pivoted at 96' to the end of the lever 97, whose other end is pivoted to the machine frame at 98. At 15 intermediate point 99, this lever also is pivoted to the cable or chain connected with the clutch mechanism. Upon energization of the solenoid winding, the armature is drawn down and lever 97 rotated, causing thus 20 actuation of the chain or cable to cause the clutch to connect the pulley with the driving shaft. To automatically cause energization of the solenoid, I insulate the stop member 39 from the machine frame by means of insulation 25 100. This stop connects through conductor 101 with one terminal of the solenoid winding, whose other terminal connects through conductor 102 with one terminal of switch 103, which is connected through conductors 30 105 and 106 with a current source. The other terminal of the switch connects directly with the machine frame. When the stock such as the bar *s* is inserted in the machine to be operated upon it is in electrical contact 35 with the machine frame, and when it reaches the stop terminal 39 in position to be operated upon, the circuit for the solenoid is closed and the clutch automatically thrown in and the machine started. As soon as the 40 severed blank is moved downwardly by the formers, the circuit is broken, but the clutch can be of a construction which, when thrown into engagement, will retain itself in engagement for one complete revolution and will 45 then automatically release. Clutches of this class are well known in the art and are not claimed herein. Therefore, although the circuit is broken, the machine will continue to run until all the operations have 50 been carried out. The clutch mechanism is then automatically disengaged and returned to its normal position by the springs 87' and 91', spring 87' connecting between the forked arm 87 and the machine frame and 55 spring 91' connecting between the treadle 91 and frame.

For the purpose of convenience in illustration and description, I have shown the dies, formers and punches to be of the particular form whereby the finished article shown in Figs. 9 and 10 is produced. Referring to Fig. 8 which illustrates the metal ribbon, after it has been stamped, the openings *a*, *b*, and *c* and the slot *d* are punched 60 by means of the respective punches *a'*, *b'*,

c', and *d'*. For the purpose of illustration, I will assume that the stock has been cut at the dotted line *l*. The stock is then advanced until it touches the stop 39. The machine is then started, and the slide descends, whereby the stock is cut by means of the knife 41 at 41'. The distance between the stop 39 and the shoulder 42 and the disposition of the punches relative to each other and to the other operating parts, 70 must be properly gaged so that the finished article may be given its proper form. This precise means, however, is shown merely for the purpose of illustration and description, and it is evident that any form of punch mechanism, dies and formers may be employed to manufacture different articles. The article formed by these dies and shown in Figs. 9 and 10 is a clip for switches, and in the prior art it has been necessary to employ three or four operations to manufacture such a clip. From the foregoing, it is evident that a clip of this kind will be produced with each stroke of the machine.

In Figs. 11 and 12, I have shown another 90 form of dies and formers which may be employed to secure another product. The ribbon metal fed into the machine when such dies are employed is shown in Fig. 13, and the shape and form of the blanks after having been stamped is shown in dotted lines in this figure. The dotted lines *x* and *y* indicate where the blanks are cut by the knife 41. The finished article formed by these dies is shown in Fig. 14, it being a clip for 100 electrical fuses which are employed for the purposes well known in the art. The lugs *g*, *g*, as shown in Fig. 14, after having been cut out, as shown in Fig. 13 in dotted line, are turned over the front of the die by means 105 of the shoulders *t*, *t* on the dies 30 and 31. This construction is clearly shown in Fig. 12. From these figures just described, it will be seen how dies of different shapes and corresponding formers may be employed for the 110 production of different articles.

From the foregoing, it will appear evident that I provide a forming and stamping machine which is of simple construction and which does not easily become disordered or 115 disarranged. I provide a device of the class described which will produce a finished article with each stroke of the machine. The machine is of such a nature that delicate adjustment is not necessary, and its operation 120 is such that an experienced operator is unnecessary, the only thing done manually being the feeding of the stock into the machine. Moreover, this feeding is entirely controlled by the mechanism described, whereby the 125 danger of improper or careless feeding is effectively eliminated. The machine is so constructed that different forms of punches and dies may be readily substituted, whereby different articles may be manufactured.

While I have herein shown and described but one embodiment of my invention, it is evident that changes and modifications could be made by those skilled in the art without departing from the spirit or scope thereof. I do not, therefore, wish to be limited to the precise construction herein shown, but

I claim as new and desire to secure by Letters Patent:

1. In a device of the class described, the combination with a reciprocating slide, of punch mechanism secured to said slide and adapted to stamp a blank fed into the machine upon the downward stroke of said slide, dies over which the blanks stamped by said punch mechanism may be formed, formers mounted in said slide for association with said dies, means for cutting said blank from the stock upon the downward stroke of said slide, a cam plate secured to said slide, and pivoted dogs controlled by said cam plate, said dogs being adapted to exert pressure upon said formers, whereby said blank is formed over said dies, upon the downward stroke of said slide.

2. In a device of the class described, the combination with a reciprocating slide, of punch mechanism secured thereto, formers pivoted in and suspended from said slide, dies with which said formers are adapted to be associated, a cam plate secured to said slide, and dogs controlled by said cam plate, said dogs being adapted to exert pressure upon said formers with the descent of the slide, whereby said formers are forced about said dies.

3. In a device of the class described, the combination with a reciprocating slide, of punch mechanism operating with said slide, a die over which blanks stamped by said punch mechanism are adapted to be formed, formers pivoted in said slide for association with said die, a cam plate operating with said slide, dogs controlled by said cam plate, said dogs being adapted to exert pressure upon said formers with the downward stroke of the slide whereby the blanks are formed about said die, and means for withdrawing said die from the formed article.

4. In a device of the class described, the combination with a reciprocating slide connected with a rotating shaft, of punch mechanism secured to said slide, formers supported by said slide, a die with which said formers are adapted to be associated, means for exerting pressure upon said formers upon the descent of the slide whereby a blank stamped by said punch mechanism may be formed over said die, an auxiliary shaft operatively connected with said shaft, a cam upon said auxiliary shaft, and a follower for said cam, said follower being connected with said die whereby said die may be withdrawn from the finished article upon the upward stroke 65 of the slide.

5. In a device of the class described, the combination with a reciprocating slide connected with a rotating main shaft, of punch mechanism secured to said slide, a die over which blanks stamped by said punch mechanism may be formed, formers pivoted in and suspended from said slide, a knife upon one of said formers for cutting said blank from said stock, a cam plate secured to said slide, pivoted dogs controlled by said cam plate, 75 said dogs being adapted to be engaged by the cam plate upon descent of the slide to exert lateral pressure against the formers to cause said blank to be drawn about said die, and cam and follower mechanism operatively 80 connected with said main shaft for causing the withdrawal of said die from the finished article upon the upward stroke of said slide.

6. In a machine of the class described, the combination with a reciprocating slide, of punch mechanism secured to said slide, formers supported by said slide, a die over which blanks stamped by said punch mechanism may be formed by said formers, and a cutting edge on one of said formers for severing the punched blanks from stock fed into the machine.

7. In a device of the class described, the combination with a reciprocating slide connected with a main shaft, of punch mechanism secured to said slide, a die over which a blank stamped by said punch mechanism may be formed, formers pivoted in and suspended from said slide, a cam plate secured to said slide, dogs controlled by said cam plate, said dogs being adapted to exert pressure upon said formers with the descent of the slide whereby said blank may be formed about said die, gripping means for securely holding said blank upon said die while said forming is taking place, and means for withdrawing said die from the finished article.

8. In a device of the class described, the combination with a reciprocating slide, of formers mounted therein, a die with which said formers are adapted to be associated over which blanks may be formed, a cam plate secured to said slide, pivoted dogs controlled by said cam plate, said dogs being adapted to exert pressure upon said formers with the descent of the slide, gripping means for securely holding the blank upon said die during the descent of the slide and for releasing said gripping means during the upward stroke of the slide, and means for withdrawing said die from the finished article.

9. In a device of the class described, the combination with a reciprocating slide connected with a main rotating shaft, of formers pivoted in and suspended from said slide, a die with which said formers are adapted to be associated and about which a blank may be formed, a grip for holding said blank securely upon said die while it is being formed, a pivoted lever connected with said

grip, and a cam which said lever is adapted to follow, said cam being mounted upon a shaft operatively connected with said main rotating shaft.

- 5 10. In a device of the class described, the combination with a reciprocating slide connected with a main rotating shaft, of formers pivoted in and suspended from said slide, a die with which said formers are adapted to 10 be associated, a grip for holding said blank securely upon said die while it is being formed, a pivoted lever connected with said grip, a cam which said lever is adapted to follow, said cam being mounted upon a shaft 15 operatively connected with said main rotating shaft, an auxiliary cam secured to said shaft, and gripping means operated by the auxiliary cam for holding said stock, said auxiliary gripping means being adapted to 20 release said stock when same is to be advanced.

11. In a device of the class described, the combination with a reciprocating slide connected with a main rotating shaft, of stamping mechanism secured to said slide, a die about which blanks stamped by said stamping mechanism may be formed, formers pivoted in and suspended from said slide for association with said die, a knife edge upon one 25 of said formers for cutting the blank from the stock upon the descent of the slide, a cam plate secured to said slide, pivoted dogs controlled by said cam plate, said dogs being adapted to be brought into engagement with 30 said formers with the descent of the cam plate whereby said formers are forced about said die, a grip for holding said blank securely upon said die during the descent of the slide, said grip being connected with a pivoted 35 lever arm, a cam which said lever arm is adapted to follow, mounted upon an auxiliary shaft operatively connected with said main shaft, auxiliary gripping mechanism operated by an auxiliary cam upon said auxiliary 40 shaft for holding said stock, and means for causing the withdrawal of said die from the finished article during the upward stroke of the slide, said grip being adapted to release said stock at the same time, said auxiliary gripping means being adapted to release 45 said stock when it is to be advanced.

12. In a device of the class described, the combination with a reciprocating slide connected with a main rotating shaft, of stamping means mounted thereon, a die over which blanks stamped by said stamping means may be formed, formers supported by said slide 50

adapted to be associated with said die upon the descent of said slide, means for exerting pressure upon said formers whereby said blank is drawn about said die, cam actuated means for securely holding said blank upon said die, said means being adapted to release its hold during the upward stroke of the slide, means for withdrawing said die from the finished article, and auxiliary cam actuated gripping means for holding the stock, said means being adapted to release the stock when it is to be advanced.

13. In a machine of the class described, the combination with reciprocating mechanism connected with a main rotating shaft for stamping and forming blanks, of a driving wheel, clutching mechanism for connecting said driving wheel with the main rotating shaft, treadle mechanism for operating the clutch mechanism, solenoid mechanism for operating the treadle mechanism, and an electrical circuit for the solenoid mechanism automatically closed upon feeding stock into the machine.

14. In a machine of the class described, the combination with a reciprocating slide frame, of forming members carried from said frame, die mechanism for coöperating with said forming members, bell crank levers pivoted to the machine frame and adapted to be engaged at one end by the frame to cause engagement at their other end with the forming members to cause said forming members to form blanks over the dies.

15. In a device of the class described, the combination with a vertically reciprocating slide frame, of forming rods pivoted to and extending downwardly from said frame, dies supported from the machine frame for co-operating with the forming rods, means for feeding blanks below the forming rods and over the die, descent of the frame causing said forming rods to engage the blank to bend the blank over the die, and bell crank levers pivoted adjacent the die and engaged at one end by the frame so that their other ends engage against the former rods to exert lateral pressure thereon whereby the blank is formed about the die.

In witness whereof, I hereunto subscribe my name this 24th day of September A. D., 1906.

JOHN CUTHBERT.
